CHILD'S ROCKING CHAIR

Radcliffe W. Hunter, 533 E. 3rd Place, Chicago, Ill., and
Stephen E. Konecnik, 1135 Broadway, Park Ridge, Ill.

Filed Aug. 22, 1961, Ser. No. 66,460

Term of patent 14 years

(Cl. D15—1)

FIG. 1

FIG. 2

FIG. 3

FIG. 4

FIGURE 1 is a front perspective view of a child's rocking chair showing our design;

FIGURE 2 is a side elevational view thereof, the view from the opposite side being identical;

FIGURE 3 is a front elevational view; and

FIGURE 4 is a rear elevational view.

The dotted lines depicting a child in FIGURES 1, 2 and 3 are for illustrative purposes only.

We claim:

The ornamental design for a juvenile chair, as shown and described.
